CLAIM

The ornamental design for a handle for fishing reel, as shown and described.

DESCRIPTION

FIG. 1 is a top, front, perspective view of a handle for fishing reel, showing my new design;

FIG. 2 is a front view thereof;

FIG. 3 is a right side view thereof;

FIG. 4 is a rear view thereof;

FIG. 5 is a left side view thereof;

FIG. 6 is a top plan view thereof; and,

FIG. 7 is a bottom plan view thereof.

The broken line showing of environment in FIGS. 1 to 7 is for illustrative purposes only and forms no part of the claimed design.
